UNITED STATES PATENT OFFICE.

STELLA BRANDT, OF NEW YORK, N. Y., ASSIGNOR TO WAITE CARPET COMPANY, OF OSHKOSH, WISCONSIN, A CORPORATION OF WISCONSIN.

DESIGN FOR A RUG.

Application filed January 3, 1929. Serial No. 29,487. Term of patent 7 years.

To all whom it may concern:

Be it known that I, STELLA BRANDT, a citizen of the United States, residing at New York city, in the county of New York and State of New York, have invented a new, original, and ornamental Design for Rugs, of which the following is a specification, reference being had to the accompanying drawing, forming part thereof.

The figure is a plan view of a rug showing my new design.

I claim:

The ornamental design for a rug, as shown.

STELLA BRANDT.
